MARKING MACHINE

Harold Ernest Elliott, Leicester, England, assignor to United Shoe Machinery Corporation, Paterson, N. J., a corporation of New Jersey

Application November 9, 1935, Serial No. 48,961
In Great Britain November 10, 1934

56 Claims. (Cl. 101—96)

This invention relates to marking machines and is illustrated herein as embodied in a machine particularly adapted for marking parts of boots and shoes, for example linings, to indicate the size and style and other characteristics of the boot or shoe.

Marking machines provided with a row of disks carrying marking characters on their peripheries, such as "1" to "9" or "a" to "z", are being extensively used for marking parts of boots and shoes. In such machines the disks are rotated to bring different marking characters into marking position and the marks are formed on the work in a single row during one operation of the machine. Under some conditions, in order to mark the necessary information upon the lining, the row of characters may be too long with the result that a portion of the marks may be illegible or may be in a position where they cannot easily be read. To overcome this and other difficulties, auxiliary type carrying plates have been provided which carry loose type pieces for making one or more rows of marks parallel to the row of marks made by the marking characters on the disks. However, the loose type pieces are relatively small and are difficult to place in position, particularly if they are hot as when used in connection with a heated head. Consequently the changing of the loose type pieces is likely to result in loss of time and production.

An object of the present invention is to provide a machine having type disks for making a double row of marks and adapted to be readily reset to change the marks. To this end a feature of the present invention resides in a mechanism embodying marking disks having marking characters on their peripheries and arranged in pairs so that alternate disks imprint the characters in one line and the remaining disks imprint the characters in an adjacent parallel line. To this end, the marking characters on one of the disks of a pair are arranged to overlap and be interposed between the marking characters on the other disk of the pair. Means are provided for separating the disks of some desired pair to separate the interdigitated characters so that the disks may be rotated relatively to each other. As illustrated, a pair of marking disks, each having a plurality of laterally extending type-carrying projections formed on the periphery of its disk and positioned to overlap the other disk, is provided with cam surfaces formed on the face of the disk which is adjacent to the other disk. These cam surfaces cooperate to separate the disks to permit the laterally extending type projections to

pass by each other when the disks are rotated relatively to each other. By the use of such a construction, two rows of marks can be formed on a work piece in a single operation of the machine and the marking characters in either row can be easily and quickly changed when desired.

Another object of the invention is to provide an improved mechanism for rotating the marking disks when it is necessary to change the marking characters in marking position and to this end another feature of the invention resides in a marking machine provided with disk-turning means comprising an actuator for each disk, the actuator for the disk to be reset being movable successively into engagement with the disk to be reset and then in a different direction to rotate the selected disk to bring a succeeding marking character thereon into marking position.

As herein illustrated, the disks are normally locked in marking position by pawls, and that one of which corresponding to the disk being reset is released, according to another feature of the invention, prior to the movement of this disk in response to a continuous movement of the disk-turning means in one direction.

With these and other objects and features in view the invention will now be described with reference to the accompanying drawings.

In the drawings,

Fig. 1 is a perspective view of the forward portion of a machine illustrating a preferred embodiment of the invention;

Fig. 2 is an exploded view illustrating a pair of marking disks;

Fig. 3 is a plan view of the head of the machine;

Fig. 4 is a detail view in side elevation, seen from the side opposite to that shown in Fig. 1, showing the mechanism for insuring rotation of the marking disks in the proper direction;

Fig. 5 is a detail view in side elevation and partly in section, in the same direction as Fig. 4, of the actuating mechanism for rotating the marking disks;

Fig. 6 is a detail view in side elevation of the mechanism for moving a selected stop member for the marking disks out of operative position;

Fig. 7 is a detail view of an operating mechanism for a feed roll for a paper strip; and

Fig. 8 is an end view of the feed roll mechanism.

The present invention is shown by way of illustration as embodied in a machine of the type disclosed in United States Letters Patent No. 1,109,938, granted September 8, 1914, on an application filed in the name of Fred Asahel Putnam. As in that machine, the marking head is mounted

at the end of a forked main lever 16 (Fig. 3) which is fulcrumed to the frame 12 (Fig. 1) on a shaft 18 and is oscillated to carry the head toward and away from the work. Oscillation of this lever 16 may be accomplished in any desired way as by a link (not shown) connected to the lever 16 and to a crank on an operating shaft (not shown).

The forward end of the lever 16 carries a hollow shaft 22 (Figs. 4 and 5) on which is mounted a plurality of marking disks 20 (Figs. 1 and 2). Each disk 20 is provided with radially extending projections 24 (Fig. 2) which carry marking characters (Fig. 1). The main body portions of disks 20 are one-sixteenth of an inch in thickness and the projections 24 are one-eighth of an inch in thickness. The projections 24 are flush with one side of the disks 20 and project one-sixteenth of an inch beyond the other sides of the disks. The laterally interengaged disks 20 are arranged in pairs so that the projections 24 on one disk 20 lie between and, hence, are interdigitated with the projections 24 on the other disk of the pair. The projections 24 on one disk 20 are so arranged that they lie close behind the corresponding projections on the other disk of the pair. In other words, the projections 24 on each disk 20 overlap the periphery of the body portion of the other with adjacent projections 24 of each disk abutting each other so that when the body portions of the disks 20 are in contact the side surfaces of these projections 24 lie in the same plane. This construction, when embodied in a plurality of pairs of coaxial disks provides two rows of marking characters (Fig. 1), one located directly behind the other. As illustrated, the outer faces of the projections 24 are located in a circle approximately four inches in diameter.

To provide for separating the disks 20 of each pair, so that one may be rotated, when it is desired to bring the marking character on another projection 24 into marking position, the inner surfaces of adjacent disks 20 of each pair are provided with cam members 26 (Fig. 2). These members 26 extend laterally of each disk 20 approximately one-sixteenth of an inch and are twelve in number, which corresponds to the number of projections 24 on each of the disks 20. The cam members 26 are nearer the centers of the disks 20 than the marking projections 24. The lateral faces 28 (Fig. 2) of the cam members 26 are parallel to the side faces of the disks 20, and the cam members 26 have inclined faces 30 extending from their lateral faces 28. These inclined faces extend toward the side faces of the disks 20 and into openings 32 formed in the bodies of the disks 20. When a pair of disks 20 is brought close together so that the marking projections 24 on the two disks 20 lie behind each other around the disks 20, the cam members 26 on each disk 20 enter the openings 32 in the other disk 20. When the disks 20 are rotated relatively to each other in the proper direction, the inclined faces 30 of the cam members 26, by their engagement and relative movement, separate the two disks 20 laterally so that the laterally extending portions of the projections 24 just pass each other. When the marking projections 24 have passed each other, the cam members 26 enter the next openings 32 and the disks 20 move into engagement with each other. When the disks 20 are thus in engagement and the projections 24 lie behind each other, there is a small gap 34 (Figs. 4 and 5) between adjacent projections. Also, when the disks 20 are in engagement with each other there is a larger gap

36 (Fig. 4) between the non-adjacent projections 24 which present relatively inclined converging sides 38 against which, as will hereinafter be described, a beveled member is pressed to align the projections on the several sets of disks.

Such axial movement of the disks is permitted only when a new character is to be selected and the disks are clamped together during printing operations. To this end, the horizontal shaft 22 which carries the disks 20 is supported at its ends by blocks 40 and 42 (Figs. 1 and 3) secured to the forked forward end of the lever 16. The disks 20 are so arranged that they are free to rotate and to move axially on the shaft. The hollow shaft 22 receives an electric heating unit 44 (Fig. 2) by which the shaft 22 and the disks 20 are heated. At each end of the row of disks 20 is a ring 46 slidably mounted on the shaft 22. Each ring 46 is arranged to bear against the outer face of an endmost disk 20 and is provided with three laterally projecting pins 48 equally spaced about its axis. The pins 48 are slidably mounted in the above-mentioned blocks 40, 42 and at their outer ends are secured in three-armed members 50, 52. The three-armed members 50, 52 are engaged at their centers by the forward ends of arms 54, 56 of a pair of rearwardly extending clamping levers 58, 60. The clamping levers 58, 60 are pivoted on upwardly extending pivot pins 62, 64, respectively, carried by the operating or main lever 16. The clamping levers 58, 60 have rearwardly extending arms between which is a spring 66 surrounding a rod 67 (Fig. 3) normally urging the forward ends of the arms toward each other and through the rings 46 pressing the marking disks 20 into close engagement with each other. The rearwardly extending arms of the clamping levers 58, 60 have threaded for adjustment in them horizontal studs 68, 70 which extend toward each other. Rotatably mounted in the rear of the operating lever 16 in suitable bearings is a cam shaft 72 (Figs. 3 and 4) which extends from right to left of the machine and has a crank 73 by which it may be turned manually. The cam shaft 72 is provided with a pair of locking cams 74, 76 which, in one position of the cam shaft, engage the heads of both the studs 68, 70 and, through the clamping levers 58, 60, press the marking disks 20 together. In another position of the cam shaft 72, a gap in one of the cams 74, 76 allows one of the clamping levers 58, 60 to move about its pivot while the other clamping lever is prevented from moving. In a third position of the cam shaft 72 conditions are reversed and that clamping lever, which was held against movement in the second position of the cam shaft 72, is now free to move on its pivot while other clamping lever which was free to move is now held against movement.

Either one of the two marking disks 20 of each pair is rotated step by step by one of a series of actuators 78 (Figs. 3 and 5). As illustrated, the machine is provided with twelve actuators 78 which correspond to the number of pairs of disks 20 in the machine and only one of which is selected as later described, for the setting of its corresponding disk at any one time. A tooth 80 (Fig. 5) on each actuator 78 enters the small gap 34 between adjacent projections 24 of each pair of disks 20 and is moved in one direction to rotate one of the disks 20 of each pair and in the opposite direction to rotate the other disk 20 of that pair. As one of the disks 20 of a pair is rotated the other disk of the pair is prevented from rotating and is allowed to move axially on the shaft 22 whereas

the disk 20 which is being rotated and its actuator 78 do not move axially.

When the disks 20 are to be rotated, the top of the right-hand disk of any pair is rotated forwardly and the top of the left-hand disk is rotated rearwardly. When the right-hand disk of a pair is rotated, the left-hand disk and all those to the left of it are moved axially to the left. When the left-hand disk of a pair is rotated, the right-hand disk and all those to the right of it are moved axially to the right. Such an axial movement of the marking disks 20 is controlled by the locking cams 74, 76 acting through the clamping levers 58, 60. If the right-hand disk 20 of the pair is to be rotated, the handle 73 is rotated by the handle 73 into a position in which the right clamping lever 60 is locked and the left lever 58 is permitted to move. If the left-hand disk 20 of the pair is to be rotated, the handle 73 is rotated in the opposite direction to lock the left-hand lever 58 and to allow the right-hand lever 60 to be moved. After rotation of any of the two marking disks 20, the cam shaft 72 is returned to its initial position so that both clamping levers 58, 60 clamp the marking disks 20 together.

The actuators 78 are pivoted on a horizontal pin 82 (Figs. 1 and 5). The pin 82 is supported in a swinging actuator frame 84, which comprises cross-rods 85 bolted to webs extending downwardly at each side of the marking disks 20, and is pivoted at 87 to the main lever 16 coaxially with the disks 20. An actuator-control bracket 86 (Figs. 1 and 5) is also pivoted on the pin 82. A short horizontal shaft 88 is rotatably mounted in one side web of the frame 84 and has secured to it a cam 90 (Fig. 5) which is engaged on its opposite sides by a fork 92 on the bracket 86. A short shaft 88 also has secured to it another cam 94 (Fig. 4) which operates in a normally stationary fork 96 (Figs. 1 and 4) secured to the lever 16 by studs 97. The shaft 88 has secured on its right-hand end a hand crank lever 98 (Fig. 1) by which it may be rotated. When the shaft 88 is rotated, the cams 90 and 94 are rotated with it. The cam 94, in cooperating with the normally stationary guideway 96, swings the shaft 88 and with it, the frame 84, bodily back and forth. The cam 90 which engages the forked member 92 of the bracket 86 causes the bracket 86 to be swung up and down. The angular relation of the cam 90 to the cam 94 is such that when the shaft 88 is rotated to reset one of the right-hand disks 20 the actuator-control bracket 86 is first actuated to move the tooth 80 on a selected one of the actuators 78 into the small gap 34 between two of the projections 24 on a selected pair of marking disks 20. Continued rotation of the shaft 88 then swings the actuator frame 84 forwardly to rotate one of the right-hand marking disks 20 a step. The cam 94 is of such a contour that the frame 84 is swung forwardly a distance equal to the distance between successive projections 24. At the end of the forward movement of the swinging actuator frame 84, the tooth 80 of the actuator 78 is withdrawn from the opening or gap 34 by the corresponding movement of the bracket 86 under the control of its cam 90 and during rearward movement of the frame 84 moves idly backward. When the shaft 88 is rotated in the opposite direction, the tooth 80 is held out of engagement with the gap 34 during the forward movement of the frame and is moved into engagement with the gap 34 by the cam 90 before 70 rearward movement of the swinging frame 84

takes place and during this latter movement rotates one of the left-hand marking disks 20 so that its top portion moves rearwardly.

To show the operator which numbers on the disks 20 are in operative position, the inclined faces 38 of the projections 24 on the disks 20 are provided with indicating characters or are left blank on those projections which lack type characters. These indicating characters are displaced from the corresponding printing characters a certain angular distance so that the former are in a position readily visible to the operator and correspond to the characters or blanks then in operative position. Pointers (not shown) of any suitable type may be placed on the blocks 40, 42 at each side of the disks 20 to tell the operator which row of indicating characters opposite the pointers corresponds to the printing character which is in operating position and will mark the work-piece.

As stated above, when a selected marking disk 20 is to be rotated, some of the disks 20, which lie to the right or left, as the case may be, will move axially on the shaft 22, having been released by a locking cam 74 or 76 on the shaft 72. As an additional safeguard against improper operation, the direction of rotation of the actuator-operating shaft 88 is controlled by mechanism also operated by the cam shaft 72. To this end, the crank 73 secured to the cam shaft 72 (Fig. 4) is provided with a crank pin 104 which has pivotally secured to it a forwardly extending link 106. The forward end of the link 106 passes through a block 108 pivoted at 107 in the forked lower end of a stop lever 110. The link 106 has on it at each side of the block 108 springs 112, 114 which allow the block 108 to move relatively to the link 106 in either direction. The pivot 107 of the block 108 is substantially in alignment with the axis 87 of the swinging actuator frame 84. The stop lever 110 is pivoted on a horizontal stud 118 extending laterally of the machine and secured in the right-hand depending portion of the actuator frame 84 about midway between the axis of the marking disk 20 and the axis of the actuating shaft 88. At its upper end the stop lever 110 is forked and each arm of the fork has secured to it a block 120 acting like a pawl. The blocks 120 are arranged to engage alternately opposite sides of a toothed wheel 122 secured to the shaft 88. When the stop lever 110 is swung in one direction or the other by its connection to the crank pin 104 on the shaft 72, a bevel edge of one of the blocks 120 is moved into engagement with the toothed wheel 122 and prevents its rotation in one direction but permits it to be rotated in the opposite direction.

If it is desired to rotate the right-hand marking disk 20 of a selected pair, performe forwardly, the cam shaft 72 is rotated by the handle 73 so that the left-hand locking cam 74 will allow the marking disks 20 at the left of the one being rotated to move axially to the left and the appropriate one of the blocks 120 of the stop lever 110 is, through the crank 104 and the link 106, moved into engagement with the toothed wheel 122 so that the shaft 88 can be rotated only in a direction to move one of the marking disks 20 forwardly. If it is desired to rotate the other of the selected pair of marking disks 20, performe rearwardly, the cam shaft 72 is rotated through 180 degrees so that the disks 20 at the right of the one being rotated can move axially to the right and the other block 120 on the stop lever is moved into engagement with the other side

of the toothed wheel 122 so that the shaft 88 can only be moved in the proper direction. The springs 112, 114 on the link 106 allow the block 123 which is in engagement with the toothed wheel 122 to click past the teeth as the shaft 88 is rotated in the direction in which its rotation is not prevented. Since the pivot 107 of the block 108 at the lower end of the stop lever 110 is substantially coaxial with the pivot 87 of the swinging actuator frame 84, the movement of the stop lever 110 is unaffected by movement of the actuator frame 84 either rearwardly or forwardly. After one or a number of marking disks 20 have been rotated, the cam shaft 72 is returned to its initial position in which the cams 74, 76 press the marking disks 20 together and both the blocks 120 on the stop lever 110 are out of engagement with the toothed wheel 122. Rotation of any of the marking disks 20 when the cam shaft 72 is in its neutral position is prevented since the marking disks 20 are held firmly pressed against each other by the action of the locking cams 74, 76.

A selected marking disk actuator 78 associated with the marking disk 20 which it is desired to rotate, is moved relatively to the other actuators 78 from an inoperative position to an operative position where its tooth 80, upon movement of the bracket 86, can engage the gap 34 between the marking projections 24 of the pair of disks 20. For this purpose, one of the actuators 78 is engaged by a lug 124 (Fig. 5) projecting from a horizontal selector shaft 126. The shaft 126 is threaded in the actuator-control bracket 86 and has an actuating handle 127 mounted on a crank arm 129. The shaft 126 is provided with a screw-thread 128 (Fig. 3) which engages a threaded sleeve 130 secured to the control bracket 86. When the selector shaft 126 is rotated by the operator through one revolution, the lug 124 is moved from one actuator 78 to the next and during its movement releases the actuator 78 with which it has been in engagement and depresses the tail of the actuator 78 into engagement with which it has been moved. Each actuator 78 has a forwardly projecting arm 131 (Fig. 5) which extends over and close to the top of the marking disks 20. These arms 131 are visible to the operator so that when the rear end of an actuator 50 is depressed the front end thereof is raised and the operator can see which actuator 78 is in operative position and which disk 20 will be moved when the shaft 88 is rotated to depress an actuator and to swing the frame 84. The forwardly extending arms 131 of the actuators 78 are depressed, i. e. held in normal position, by leaf springs 132 which normally hold the rear ends of the actuators against the selector shaft 126.

60 A row of stop pawls 134 (Fig. 5) are provided which prevent rotation of all of the marking disks 20 except the one which is being rotated. The stop pawls 134 are slightly thinner than the disks 20 and are slidably mounted in the main lever 16 at the rear of the disks. The stop pawls 134 are urged forwardly into engagement with the small gaps 34 between the marking projections 24 by leaf springs 136 (Fig. 5) secured to a cross bar 137 attached to lugs 139 and 141 (Fig. 70 3) on the lever 16. The top of each pawl 134 has a notch 138 and a tooth 140 formed in the lower end of a depending stop pawl arm 142 is slightly less than the width of the pawls 134 and projects into one of these notches 138 which, when aligned, 75 form a groove. The arm 142 is secured on a

horizontal shaft 144 (Figs. 3 and 5) which extends laterally of the machine and is rotatably and slidably mounted in the lever 16. An upwardly and forwardly extending plate 146 (Fig. 6) is mounted on the left-hand end, as seen from the front of the machine, of the stop pawl shaft 144 (Fig. 1). The plate 146 is mounted on the shaft 144 between collars 148, 150 (Figs. 3 and 6) secured on the shaft 144 so that the plate 146 and the shaft 144 can move as a unit axially of the shaft. The plate 146, however, is free to rotate relatively to the shaft 144. The plate 146 has formed in it a slot 152 (Fig. 6) through which passes one end of the shaft 126. Collars 158, 160 (Fig. 3), between which is located the plate 146, 15 are secured to the selector shaft 126. By this construction the shaft 144 moves lengthwise with the shaft 126 and the tooth 140 on the arm 142 is moved along the stop pawls 134 as the lug 124 on the selector shaft 126 is moved along the actuators 78. The shaft 144 has splined to it another depending arm 162 (Fig. 6) which at its lower end is pivotally connected to the rear end of a forwardly extending bar 164. The forward end of the bar 164 is provided with a pair of arms 168, 170 extending upwardly and downwardly from the bar 164. The front faces of these arms 168, 170 are engaged by pins 172, 174 extending laterally from an arm 176 pivoted at 179 on the actuator frame 84 coaxially therewith and hence with the disks 20. The arm 176 extends upwardly and rearwardly and at certain times in the cycle of movement of the actuator frame 84 is engaged by a rib 177 (Fig. 6) on the selector shaft 126 and is moved in one direction or the other on the actuator frame pivot to withdraw one of the stop pawls 134 from engagement with a gap 34 between the marking projections 24. When the actuator-control bracket 86 is swung on its pin 82, as above described, to move the tooth 80 of the selected actuator 78 into engagement with the gap 34 between the marking projections 24, the selector shaft 126 is swung downwardly during part of the cycle of movement of the frame 84 so that during its forward or rearward swinging movement, as the case may be, with the actuator frame 84 it engages the upper end of the arm 176 and through one of the pins 172, 174 moves the bar 164 and actuates the stop pawl shaft 144 to withdraw the selected stop pawl 134 from the gap 34 between the marking projections 24 so that the selected disk 20 may be rotated. When the actuator-control bracket 86 is swung on its pin 82 so that the actuator tooth 80 is withdrawn from the disks 20, the selector shaft 126 is raised so that it releases the arm 176 and allows the corresponding stop pawl 134, previously withdrawn, to be moved by its spring 136 into engagement with the gap 34. During the movement of the actuator frame 84 when the actuator tooth 80 is out of engagement with the disks 20, the selector shaft 126 moves idly above the upper end of the arm 176. By this means the selected stop pawl 134 is only withdrawn from the disks 20 while a disk 20 is being set.

When the actuator frame 84 has been returned to its initial position, the selector shaft 126 is out of engagement with the arm 176 and all the stop pawls 134 are in engagement with the gaps 34 between the marking projections 24 on the marking disks 20. When the parts are in this position, the machine may be operated to mark a work-piece. If the selector shaft 126 is rotated when the actuator frame 84 is not in its initial position, damage to the machine parts may re-

sult. In this position one of the stop pawls 134 will be out of engagement with its pair of disks 20 and since the stop pawl 134 is out of line with the line of notches 138 in the stop pawls 134 the depending arm 142 on the selector shaft 126 will be unable to move along the row of stop pawls 134.

To prevent rotation of the selector shaft 126 under these conditions, a sleeve 178 (Fig. 3) is mounted on the right-hand end of the selector shaft 126. The sleeve 178 is kept from endwise movement by an arm 179a held on the end of the pin 82 and is splined to the shaft 126 so that it rotates therewith but permits the shaft 126 to move endwise through the sleeve 178. The sleeve 178 has formed on it a flange 180 which is provided with a notch 182 engaged by a pawl 184 (Fig. 4) pivoted to the pin 82. The pawl 184 has a tail 186 which is moved into engagement with an adjustable screw 190 in the actuator frame 84 when the tooth 80 of the selected actuator 78 is moved into engagement with its disk 20, the movement taking place as follows. When the actuator control bracket 86 (Fig. 5) is rotated in a clockwise direction about its pivot pin 82 to move tooth 80 on the selected actuator 78 into engagement with its disk 20, it will move the selector shaft 126 together with its attached sleeve and flange 178, 180 in the same direction, as the shaft 126 is also mounted upon the bracket 86. Movement of the flange 180 about the pin 82 will cause the pawl 184 to rotate in the same direction about the pin 82, which also forms the pivot for the pawl, thus moving the pawl tail 186 into engagement with the adjustable screw 190. Engagement of the pawl tail 186 with the screw 190 will prevent movement of the pawl away from the flange 180 and will thus hold the pawl 184 positively in engagement with the notch 40 in the flange thereby preventing rotation of the shaft 126 while the actuator is in engagement with its disk 20.

When the actuator frame 84 is in its initial or rest position and the tooth 80 on the selected actuator 78 is out of engagement with its disks 20 and all the stop pawls 134 are in engagement with the disks 20, all of the notches 138 in the upper faces of the stop pawls 134 are in line. In this position the tail 186 of the pawl 184 is moved away from the screw 190 and is yieldingly pressed by a spring 192 in the actuator frame 84 into engagement with the notch 182 in the flange 180 of the sleeve 178 so that, upon rotation of the shaft 126, the pawl 184 slips out of the notch 182 and rides on the periphery of the flange 180, until, after the completion of one revolution of that shaft, it again enters, yieldingly, the notch 182. As will be apparent from an inspection of Figure 4, the arrangement of the screw 190, the pawl 184 and the collar 180 is such that when the pawl 184 is out of the notch 182 and in engagement with the periphery of the flange, the pawl tail 186 will be substantially in engagement with the adjustable screw 190 thus preventing clockwise rotation of the frame 84 about the pin 82, as viewed in Fig. 4, and consequently preventing movement of the tooth 80 on the selected actuator into engagement with its disk 20. The selector shaft 126 can then be rotated and will move endwise to move its lug 124 along the actuators 78 and the stop pawl tooth 140 along the groove formed by the aligned notches 138 in the stop pawls 134.

The pawl 184 and the notch 182 indicate to the

operator when a complete revolution of the selector shaft 126 has been made.

Further assurance of proper alinement of the row of characters to be printed is had by a mechanism including an eccentric 194 (Figs. 3 and 4) 5 on the cam shaft 72 and which is engaged by a fork 196 on the rear end of a lever 200. This lever 200 is pivoted on a horizontal shaft 202 extending laterally of the machine between the arms of the forked lever 16. The forward end 10 of the lever 200 has removably secured to it a marking bar 204 which carries at its forward end a marking plate 206 which is arranged to be positioned beneath the marking disks 20. When the cam shaft 72 is in its neutral position in which all 15 disks 20 are pressed axially together, the plate 206 is raised into engagement with the marking disks 20. The plate 206 has formed in it an opening 208 having beveled front and rear walls 20 which engage the inclined faces 38 on the marking projections 24 at the bottom of the disks 20 which stamp the work. The opening 208 extends across the whole of the disks 20 and when the plate 206 is pressed upwardly the beveled walls 25 of the opening 208 align the whole row of projections 24 if these do not happen to be in alinement. When the cam shaft 72 is rotated in either direction from its neutral position, the eccentric 194 lowers the plate 206 and the marking disks 20 can be rotated as hereinbefore described. The lower face of the plate 206 surrounds the lowermost marking projections 24 and may have auxiliary marking characters fixed on it; for example, if the machine is to be used to mark shoe linings, the plate 206 at the rear 30 of the marking projections 24 on the disks 20 may have the name of the shoe manufacturer on it, and at the sides of the marking disks 20 and in line with the lowermost characters on them the plate 206 may have stamps marking 40 on the lining the words size, last, style and order, indicating the size of shoe, number of last, style of shoe and order number. The marking disks 20 will be rotated so that the desired number will be stamped on the work-piece in line with 45 and at the same time as the words on the plate. The numbers will be between the words and may be separated by blank spaces.

A reel 210 (Fig. 1) on which is wound a continuous band of marking paper 211 which is pressed 50 against the work-piece by the heated characters on the disks is rotatably mounted on a spindle 212 secured to the right-hand side of the lever 16 and the paper passes from the reel 210 beneath a freely rotatable guide roll on the right-hand side of the lever 16. The paper 211 then passes beneath and close to the marking disks 20 and marking plate 206. Thence the paper passes between a paper feed roll 214 and a co-operating presser roll 216. The roll 216 may be 60 swung away from the feed roll 214 to allow the paper to be inserted between the rolls. The feed roll 214 is rotatably mounted on a bracket 218 (Figs. 1, 7 and 8) secured to the marking lever 16 and the presser roll 216 is urged toward the 65 feed roll 214 by a spring 220. The feed roll 214 is driven by a shaft 222 extending rearwardly from the feed roll 214. This shaft 222 is rotatably mounted in the lever 16 and can move lengthwise therein a small amount. The shaft 222 at 70 its forward end has clutch teeth 224 which, when the shaft 222 is moved lengthwise, engage co-operating clutch teeth 226 on the feed roll 214. The shaft 222 has formed in it a spiral groove 228 which is engaged by a pin 230 fixed in a block 75

232 slidingly mounted on the shaft 222 and guided in guideways formed on the main lever 16. The block 232 is adjustably connected by a rearwardly extending link 234 to the slotted portion of a lever 5 236 (Fig. 1) pivoted on the previously mentioned horizontal shaft 18 extending laterally of the machine and secured in the machine frame 12. The latter lever 236 is connected by a second rearwardly extending link (not shown) to a crank 10 on the crank shaft which actuates the lever 16 so that as the marking disks 20 are being moved toward the work and before they reach the work the block 232 is moved forwardly and first moves the shaft 222 forwardly lengthwise to move the 15 clutch teeth 224 on the shaft 222 into engagement with the clutch teeth 226 on the feed roll 214 and rotates the shaft 222 and feed roll 214 to feed a fresh length of marking paper beneath the marking disks 20. While the marking disks 20 are being raised the block 232 is moved rearwardly and first disengages the clutch faces and then rotates the shaft 222 idly. At this time the 20 presser roll 216 is held by a pawl and ratchet 238. The marking paper, which is of a width to 25 suit the stamping, is fed such a distance during each cycle of the machine that a fresh strip of paper is positioned beneath the marking head during each cycle of the machine.

A guard 240 (Fig. 1) extends across the front 30 of the lower part of the disks 20 and its lower edge is just above the upper surface of a work support 242 which is secured to the machine frame 12. The work-piece to be marked is passed beneath the guard 240 and the guard 240 prevents 35 the operator's fingers from being accidentally placed between the work support 242 and disks 20 and injured by the disks 20 as they descend to mark the work-piece. The guard 240 is in the form of a grid through which the operator 40 can view the work when positioned beneath the disks 20. The guard 240 is secured to the left-hand side of the machine frame by a bar 244 so shaped that the operator's left hand can approach close to the left-hand side of the work 45 support 242 below the upper surface thereof when holding one end of a work piece supported on the work support 242 but is prevented from being placed on the work support 242 from the side thereof. The guard 240 has pivoted to its right-hand side a rearwardly extending finger 245 connected to a bell crank 246 which is normally raised by a spring 248 so that the finger 245 is at about the level of the upper surface of the work support 242 and the right-hand end of the work-piece 50 passes between the right-hand side of the work support 242 and the finger 245 and is held by the operator's right hand which is below the finger 245 and is prevented by it from being placed on the work support 242. As the disks 20 descend, 55 the finger 245 is engaged by the marking paper beneath the guide roll at the right of the disks 20 beneath which the paper passes and is depressed slightly thereby and may push the operator's right hand or the fingers thereof downwardly. The front and sides of the work support 242 are thus guarded by the guard 240, the bar 244 and the finger 245, and the operator's thumbs or fingers cannot be placed on the top of the work support 242. 60

70 Although the machine has been described in detail, it is believed to be advisable for a clearer understanding of the invention to summarize briefly the operation of the machine. After it has been determined which disk 20 of a pair is to be rotated, the cam shaft 72 is rotated to unlock one

of the levers 58, 60 to permit axial movement of the disks 20 at the left or the right of the selected disk, as the case may be, in the proper direction. The shaft 126 is then rotated to bring the selector lug 124 into engagement with the actuator 5 78 associated with the selected disk and to move the actuator toward the disk 20. The handle 98 is then rotated to rotate the shaft 88 with its cam 90 and thereby to oscillate the swinging frame 84. This will move the selected actuator 78 into 10 engagement with its disk 20 and will rotate the disk 20 a step to move the next marking character into marking position. The handle 98 may be rotated as many times as necessary to bring the desired marking character into marking position. 15 After this, the cam shaft 72 is returned to its initial position to lock the marking disks 20 in position on the support 22 and to bring up the marking plate 206, thereby to align the double row of characters which are in printing position. 20 The disks are then all locked by the pawls 134 as well as by the plate 206 and the machine may be operated as many times as desired to print these selected characters.

Having thus described my invention, what I 25 claim as new and desire to secure by Letters Patent of the United States is:

1. A plurality of marking disks having marking characters on their peripheries, the marking characters on one of said disks overlapping the 30 marking characters on the other disk, and means for separating said disks to permit the marking characters on said disks to pass by each other when the disks are rotated relatively to each other.

2. In a marking machine, a pair of marking disks disposed side by side for rotation about a common axis, said disks being laterally inter-engaged against rotation relatively to each other in one direction only, means for selectively rotating said disks to reset them, and means actuated by rotation of said disks relatively to each other for moving a selected disk axially to disengage it from an adjacent disk.

3. In a marking machine, a plurality of rotatably mounted marking disks, and means for resetting said disks constructed and arranged selectively to rotate them, each of said disks having means thereon arranged to cooperate with an adjacent disk to prevent their relative rotation in 45 one direction and to effect their axial separation when rotated relatively to each other in the opposite direction.

4. A plurality of marking disks having marking characters on their peripheries, the marking 55 characters on one of said disks overlapping the marking characters on the other disk, and means on one of said disks for separating the disks to permit the marking characters on the disks to pass by each other when the disks are rotated 60 relatively to each other.

5. A pair of marking disks having marking characters on their peripheries, the marking characters on one of said disks overlapping the marking characters formed on the other disk, 65 and means formed on said disks for producing relative axial movement between said disks to permit the marking characters on one disk to pass by the marking characters on the other disk when one of the disks is rotated.

6. A pair of marking disks having marking characters on their peripheries, the marking characters on one of said disks overlapping the marking characters formed on the other disk, 70 and means formed on the adjacent surfaces of 75

said disks for moving one of the disks axially relatively to the other when one of the disks is rotated.

7. A pair of marking disks having marking characters formed on their peripheries, the marking characters on one of said disks being located behind the marking characters on the other disk, and means formed on the adjacent surfaces of said disks for moving one of the disks axially relatively to the other to permit the marking characters on said disks to pass each other.

8. A pair of marking disks having marking characters formed on their peripheries, the marking characters on one of said disks being located behind and substantially in alignment with marking characters formed on the other disk, and cam members on said disks for causing relative axial movement of said disks to permit the marking characters on said disks to pass each other when the disks are relatively rotated.

9. A pair of marking disks having marking characters formed on their peripheries, the marking characters being formed on laterally extending projections with the projections on one disk overlapping the projections on the other disk, and means for separating the disks to permit the projections to pass by each other when the disks are relatively rotated.

10. A pair of marking disks having marking characters, laterally extending projections formed on the periphery of the disks with the projections on one disk overlapping the projections on the other disk, and cam surfaces formed on the adjacent faces of said disks for separating the disks to permit the projections to pass by each other when the disks are rotated relatively to each other.

11. A pair of marking disks having laterally extending projections carrying marking characters, the projections on one of said disks overlapping the projections on the other disk, the projections on each disk being substantially twice the thickness of the body of the disk, and means on said disks for separating the disks to permit the projections to pass by each other when the disks are rotated relatively to each other.

12. In a marking machine, a support, pairs of marking disks rotatably mounted on said support, marking characters on said disks, the marking characters on one of the disks of a pair overlapping the marking characters of the other disk of the pair, means arranged to rotate said disks, and cam surfaces on the adjacent surfaces of the disks of a pair for separating the disks to permit the overlapping marking characters to pass by each other when one of said disks of a pair is being rotated.

13. In a marking machine, a plurality of pairs of marking disks, a support on which said disks are rotatably mounted, marking projections on said disks, the projections on one of the disks of a pair overlapping the projections on the other disk of the pair, cam surfaces on the adjacent surfaces of the disks of a pair for separating the disks to permit the projections to pass each other when the disks are rotated relatively to each other, said cam surfaces being arranged to prevent rotation of each disk in one direction, and means for rotating the disks.

14. In a marking machine, a plurality of pairs of marking disks, a support on which said disks are rotatably mounted, marking projections on said disks, the projections on one of the disks of a pair being arranged to overlap the projections on the other disk of the pair, cam surfaces on

the adjacent surfaces of the disks of a pair arranged to prevent rotation of each disk in one direction and to separate the disks to permit the projections on the disks to pass each other when the disks are rotated relatively to each other in 5 opposite directions, and means arranged to rotate one of said disks in one direction to bring a marking character on that disk into marking position.

15. In a marking machine, a plurality of marking disks, a support on which the disks are rotatably mounted, marking projections on said disks, the projections on one of the disks of a pair being located behind and overlapping the projections on the other disk of the pair, cam 15 surfaces on the adjacent surfaces of the disks of a pair arranged to prevent rotation of each disk in one direction and arranged to separate the disks to permit the projections on the disks to pass by each other when the disks are rotated 20 relatively to each other, and means arranged to rotate the disks to bring a marking projection into marking position.

16. In a marking machine, a plurality of marking disks, a support on which the disks are rotatably mounted, marking projections on said disks, the projections on one of the disks of a pair being located behind and overlapping the projections on the other disk of the pair, cam surfaces on 25 the adjacent surfaces of the disks of a pair arranged to prevent rotation of each disk in one direction and arranged to separate the disks to permit the projections on the disks to pass by each other when the disks are rotated relatively to each other, means for preventing rotation of 30 one of the disks of a pair, and means for rotating the other disk of the pair to bring a marking projection into marking position.

17. In a marking machine, a plurality of marking disks, a support on which said disks are 40 mounted, a frame pivotally secured to said support, a plurality of members mounted in said frame arranged to be brought into engagement with the disks, means for selectively engaging said members to move one of said members toward said disks, and means for moving a selected 45 member and said disk.

18. In a marking machine, a plurality of marking disks, a support on which said disks are mounted, a frame pivotally secured to said support, a plurality of fingers pivotally mounted on 50 said frame arranged to be moved into engagement with said disks, a member for selectively engaging said fingers to move a finger toward a disk, and means for moving said frame and a 55 selected finger to rotate said disk to bring a marking character on said disk into marking position.

19. In a marking machine, a plurality of pairs of marking disks, a support on which the disks 60 are mounted, a swinging frame pivotally secured to said support, a bracket pivotally secured to said frame, a plurality of fingers pivotally secured to said bracket and arranged to be moved into engagement with said disks, a member mounted 65 in said bracket for selectively engaging one of said fingers for moving said finger toward its associated disk, and means for swinging said frame to rotate said disk to bring a character on said disk into marking position.

20. In a marking machine, a plurality of pairs of marking disks, a support on which the disks are mounted, a swinging frame pivotally secured to said support, a bracket pivotally secured to said frame, a plurality of fingers pivotally secured 75

- to the bracket arranged to be moved selectively into engagement with said disks, a member mounted in the bracket for selectively engaging one of said fingers to move said finger toward its associated disk, a cam arranged to engage the bracket to rotate said bracket to move the selected finger into engagement with its disk, and means for swinging the frame to cause the finger to rotate the disk to bring a character on said disk into marking position.
21. In a marking machine, a plurality of pairs of marking disks, a support on which the disks are mounted, a swinging frame pivotally secured to said support, a bracket pivotally secured to the frame, a plurality of fingers pivotally secured to said bracket arranged to be moved selectively into engagement with said disks, a member mounted in said bracket for selectively engaging one of said fingers for moving said finger toward its associated disk, a shaft mounted in said frame, a cam secured to said shaft arranged to engage said bracket to rotate said bracket to move the selected finger into engagement with its disk, and means on said shaft arranged to rotate said frame about its axis to rotate the disk to bring a marking character on said disk into marking position.
22. In a marking machine, a plurality of pairs of marking disks, a support on which the disks are mounted, a swinging frame pivotally secured to said support, a bracket pivotally secured to said frame, a plurality of fingers pivotally secured to said bracket arranged to be selectively moved into engagement with said disks, a member mounted in said bracket for selectively engaging one of said fingers for moving said finger toward its associated disk, a shaft mounted in said frame, a cam secured to said shaft and arranged to engage said bracket to rotate said bracket to move the selected finger into engagement with its disk, a stationary bracket secured to said support, and a second cam mounted on said shaft and arranged to engage said stationary bracket to rotate said frame to bring a marking character on the disk into marking position.
23. In a marking machine, a support, pairs of marking disks rotatably mounted on said support, marking characters on said disks, the marking characters on one of the disks of a pair being located behind and in alinement with the marking characters on the other disk of the pair, means for rotating one of the disks of a pair, means for preventing rotation of the other disk of the pair, and means on said disks for axially moving the disks to permit the marking characters on each of the disks of the pair to pass by each other.
24. In a marking machine, a support, pairs of marking disks rotatably mounted on said support, marking characters on said disks, the marking characters on one of the disks of a pair being located behind and in alinement with marking characters on the other disk of the pair, means for relatively rotating the disks, means for selectively locking the disks against rotation, and means on said disks for axially moving one of the disks of a pair to separate the disks when the other disk of the pair is rotated.
25. In a marking machine, a support, a plurality of marking disks rotatably mounted on said support, means for selectively rotating the disks, means for preventing axial movement of the disks in one direction when a selected disk is being rotated to bring a marking character on said disk into marking position, and means for

moving the disks axially in the other direction when one of the disks is rotated.

26. In a marking machine, a plurality of pairs of marking disks, a support for said disks, marking characters on said disks, the marking characters on one disk of a pair overlapping the marking characters on the other disk of the pair, means for preventing axial movement of the disks in one direction when one disk is being rotated to bring a marking character into marking position, means for preventing rotation of the other disks, and means on the disks of each pair for moving the disks axially relatively to each other to move the marking characters on said disks out of overlapping relation when one of the disks of the pair is being rotated.

27. In a marking machine, a plurality of laterally interengaged marking disks, a support on which said disks are mounted, means for locking the disks against axial movement, means for moving some of the disks axially to permit one of the disks to be rotated, means for releasing the locking means to permit axial movement of the disks, and means for rotating the marking disks to bring a marking character into marking position.

28. In a marking machine, a plurality of marking disks, a support on which said disks are mounted for rotative and axial movement, levers for controlling the axial movement of said disks, means for locking the levers to hold the disks against axial movement, means on said disks for moving the disks axially when one of the disks is rotated, said locking means being movable to release said levers to permit axial movement of the disks, and means for rotating the marking disks to bring a marking character into marking position.

29. In a marking machine, a plurality of marking disks, a support on which said disks are mounted for rotative and axial movement, levers for controlling the axial movement of said disks, cam members arranged to release one of said levers to permit axial movement of the disks, means on said disks for moving the disks axially when one of the disks is rotated, and means for rotating the marking disks to bring a marking character into marking position.

30. In a marking machine, a plurality of pairs of marking disks, a support on which said disks are mounted, projections on said disks carrying marking characters, the projections on one of said disks of a pair being located behind and overlapping the projections on the other disks of the pair, means for locking the disks against axial movement, means for releasing the locking means to permit axial movement of part of the disks, means on said disks for separating the disks of a pair to permit the projections on one of the disks of the pair to pass by the projections on the other disk of the pair when one of the disks of the pair is rotated, and means for rotating the disks to bring a marking character into marking position.

31. In a marking machine, a plurality of pairs of marking disks, a support on which said disks are mounted for rotative and axial movement, projections on said disks carrying marking characters, the projections on one of the disks of a pair being located behind and overlapping the projections on the other disk of the pair, means for controlling the axial movement of said disks, cam members arranged normally to lock said levers whereby said disks are held against axial movement, means for operating said cams to release one of said levers to per-

mit axial movement of a portion of the disks when one of said disks is rotated, cam surfaces on the adjacent faces of said pairs of disks for separating the disks to permit the projections on the 5 disks of the pair to pass by each other when one of said disks is rotated, and means for rotating the disks.

32. In a marking machine, a plurality of pairs of marking disks, the disks of each pair being arranged for rotation in opposite directions, a support on which said disks are mounted, projections on said disks carrying marking characters, the projections on one of said disks of a pair being located behind and overlapping the 10 projections on the other disk of the pair, means on said disks for separating the disks of a pair to permit the projections on the disks to pass each other when one of the disks of the pair is rotated, means for preventing axial movement of 15 said disks prior to the rotation of one of said disks, means for releasing the last-mentioned means to permit axial movement of the disks, and means for rotating the disks to bring a marking projection into marking position.

33. In a marking machine, a plurality of pairs of marking disks, each disk having type carrying projections arranged to overlap the projections on the other disk with which it is paired, the right-hand disk of each pair being arranged for rotation in one direction and the left-hand disk 20 of each pair being arranged for rotation in the opposite direction, a support on which said disks are mounted, means for locking the disks against axial movement, said last-mentioned means being arranged to permit axial movement of the 25 disks to the left of the one being rotated when the right-hand disk of a pair is to be rotated and to permit axial movement of the disks to the right when the left-hand disk of a pair is being rotated, means for rotating the disks, and means for separating the disks of a pair to permit the 30 projections on one disk of a pair to pass by the projections on the other disk of the pair when one of the disks of the pair is rotated.

34. In a marking machine, a plurality of pairs of marking disks, the right-hand disk of each pair being arranged for rotation in a direction away from the operator and the left-hand disk of each pair being arranged for rotation toward the operator, a support on which said disks are 35 mounted, means for locking the disks against axial movement, said last-mentioned means being arranged to permit axial movement of the disks to the left of the one being rotated when the right-hand disk of a pair is to be rotated and to permit axial movement of the disks to the 40 right when the left-hand disk of a pair is being rotated, means for rotating the disks, and means connected to the locking means for insuring that 45 the right-hand disk of a pair will be rotated in a direction away from the operator and that the left-hand disk of the pair will be rotated in a direction toward the operator.

35. In a marking machine, a plurality of pairs 50 of marking disks, an actuating finger associated with each pair of disks and arranged for movement toward said disks, means for moving a selected finger toward said disks, a locking member associated with each pair of disks, means for moving a selected locking member out of engagement with its associated pair of disks, and connections between the first-mentioned means and the last-mentioned means for insuring that the 55 locking member will be withdrawn from the pair

of disks with which a selected actuating finger has been moved into engagement.

36. In a marking machine, a plurality of pairs of marking disks, an actuating finger associated with each pair of disks, a member arranged to 5 engage a selected finger for moving said finger toward the pair of disks, a locking finger associated with each pair of disks, a releasing member for moving a locking member out of engagement with its associated disk, and connections between 10 the first-mentioned member and the releasing member for maintaining said members in alignment with each other.

37. In a marking machine, a plurality of pairs of marking disks, a bracket, a plurality of actuating fingers pivotally mounted in said bracket, one of said fingers being associated with each pair of disks, a selecting member mounted in said bracket for moving a selected finger toward its associated disk, a locking member associated with 15 and normally in engagement with each pair of disks, a releasing member for moving a locking member out of engagement with its associated pair of disks, connections between the selecting member and the releasing member to move the 20 releasing member into alignment with the pair of disks toward which a selected actuating finger has been moved by the selecting member, and means for moving the bracket on which the actuating fingers are mounted to rotate one of the 25 disks of the pair.

38. In a marking machine, a plurality of pairs of marking disks, a bracket, a plurality of actuating fingers pivotally mounted in said bracket, one of said fingers being associated with each 35 pair of disks, a selecting member mounted in said bracket for moving a selected finger toward its associated disk, a locking member associated with and normally in engagement with each pair of disks, a releasing member for moving a locking 40 member out of engagement with its associated pair of disks, means connected to the selecting member for moving the releasing member into alignment with the stop finger associated with the selected pair of disks, means for operating the releasing member to move the locking member out of engagement with its associated pair of disks, and means for moving said bracket to rotate one of the disks of the pair after the locking 45 member has been moved out of engagement with the pair of disks.

39. In a marking machine, a support, a marking disk rotatably mounted thereupon, a frame carrying an actuating member adapted to engage said disk and to swing about the axis of said support to reset said disk, and means for moving said actuating member approximately radially into and out of engagement with the disk.

40. In a marking machine, a support, a marking disk rotatably mounted thereupon, means for 55 resetting said disk comprising a frame mounted to move to and fro and having an actuating member mounted thereon to swing into and out of engagement with said disk, and means for swinging said member into engagement with said disk 60 at the beginning of one part of the to-and-fro movement of said frame.

41. In a marking machine, a support, a plurality of marking disks rotatably mounted thereupon, means for resetting said disks comprising 70 a swinging frame and disk actuating members disposed normally out of engagement with the disks, and means constructed and arranged to move a selected actuating member into engage- 75

ment with its associated disk during a portion of the swinging movement of said frame.

42. In a marking machine, a plurality of pairs of marking disks, means for resetting said disks comprising actuators one of which is associated with each pair of disks, said actuators being mounted for reversed movement in opposite directions to rotate said disks, and means for selectively moving said actuators into engagement with one of the disks of a pair at the beginning of one of its said movements.

43. In a marking machine, a plurality of disks rotatably mounted in the machine, a frame swingably mounted about an axis concentric with that of the disks, a plurality of actuating fingers carried by said frame, locking members for said disks, and selective means for moving a finger toward one of the disks and for releasing the corresponding locking means.

44. In a marking machine, a plurality of marking disks, a swinging frame associated therewith, a plurality of actuating fingers on the frame, and cam means for moving a selected finger into engagement with a disk and then swinging the frame to turn the disk.

45. In a marking machine, a plurality of marking disks each having a plurality of marking characters thereon, locking pawls associated with said disks, oscillatable disk-turning means, and means actuated by a continuous movement of said turning means in one direction for successively releasing a selected pawl and rotating the disk associated therewith to bring a succeeding marking character on said disk into marking position.

46. In a marking machine, a plurality of marking disks, locking pawls associated with individual disks, oscillatable means having a disk-engaging member, and means rotatable in opposite directions for turning a disk by engagement of said member in one direction or the other, and means for releasing the selected pawl during a portion of the cycle of the oscillatable means, said releasing action occupying a different portion of the cycle depending upon the direction of rotation of said means.

47. In a marking machine, a plurality of marking disks provided with peripheral projections which may be arranged in rows, a plate mounted for movement to engage a row of projections to align them, means for clamping said disks together by pressing axially against the disks, and interrelated operating means for said plate and said clamping means.

48. In a marking machine, a plurality of rotatably mounted marking disks, an actuator for rotating a disk, mounted for oscillation in reversed cycles when moving a disk forward or backward, means for locking said disks together, and interconnected operating means for said actuator and said locking means.

49. In a marking machine, a plurality of rotatably mounted marking disks, means for selecting a disk to be rotated, movable means for rotating a selected disk, and means adjacent to said selecting means and said movable means and con-

trolled from the disk rotating means constructed and arranged to prevent movement of the selecting means when the movable means is out of its initial position.

50. In a marking machine, a plurality of rotatably mounted marking disks, means for selecting a disk to be rotated, actuating means for rotating the selected disk, said actuating means being movable into and out of engagement with the selected disk, and means adjacent to said selecting means and said actuating means and controlled from the selecting means for preventing movement of the actuating means into engagement with the disk when the selecting means is out of disk designating position.

51. In a marking machine, a plurality of rotatably mounted marking disks, an oscillatable actuator for turning a disk, a rotatably mounted selector to determine which disk shall be rotated, and means for preventing rotation of said selector when the actuator has been oscillated away from its normal position.

52. In a marking machine, a plurality of rotatably mounted marking disks, means for selecting a disk to be rotated, actuating means for rotating the selected disk, and interlocking means adjacent to said actuating means and said disk rotatable means and under the control of both of said means for preventing rotation of the disks by the actuating means when the selecting means is out of its disk designating position and for preventing operation of the disk selecting means when the disk actuating means is out of its initial position.

53. In a marking machine, a plurality of marking disks, locking pawls for said disks, means for resetting said disks comprising a plurality of actuators, a selector mounted and arranged to swing an actuator into engagement with the disk to be reset, and means for releasing a single pawl movable with said selector whereby only the pawl for the disk which is to be reset is disengaged therefrom.

54. In a marking machine, a plurality of rotatably marking disks, and means for selectively rotating said disks to reset them, the disks of each pair having cooperating surfaces at least one of which is inclined and which are arranged axially to separate the disks of that pair of which one disk is rotated.

55. In a marking machine, a plurality of pairs of rotatably mounted marking disks, and means for selectively rotating said disks to reset them, the disks of each pair having interengaging cam members for axially separating the disks of a pair when one is reset.

56. In a marking machine, a plurality of pairs of rotatably mounted marking disks, and cam members on each disk arranged to cooperate with the other disk of a pair normally to prevent the rotation in one direction of the disks of each pair relatively to each other, said cam members cooperating to separate axially the disks of a pair when rotated relatively to each other in the opposite direction.

CERTIFICATE OF CORRECTION.

Patent No. 2,150,272.

March 1st, 1939.

HAROLD ERNEST ELLIOTT.

It is hereby certified that error appears in the printed specification of the above numbered patent requiring correction as follows: Page 10, second column, line 1^{1/4}, claim 5^{1/4}, before the word "marking" insert mounted; and that the said Letters Patent should be read with this correction therein that the same may conform to the record of the case in the Patent Office.

Signed and sealed this 3rd day of October, A. D. 1939.

Henry Van Arsdale,

Acting Commissioner of Patents.
